UNITED STATES PATENT OFFICE.

BURNS D. LOCKWOOD, OF BELLEVUE, PENNSYLVANIA, ASSIGNOR TO PRESSED STEEL CAR COMPANY, OF PITTSBURGH, PENNSYLVANIA, A CORPORATION OF NEW JERSEY.

UNDERFRAME FOR RAILWAY-CARS.

1,157,707.

Specification of Letters Patent.

Patented Oct. 26, 1915.

Application filed December 7, 1911. Serial No. 664,321.

To all whom it may concern:

Be it known that I, BURNS D. LOCKWOOD, a citizen of the United States, residing at No. 444 Dawson avenue, Bellevue, in the 5 county of Allegheny and State of Pennsylvania, have invented certain new and useful Improvements in Underframes for Railway Cars, of which the following is a specification.

10 My invention relates to the underframes of railway cars, and especially to underframes that are constructed wholly or partly of metal and has for its object to overcome certain objectionable features existing in 15 such underframes as now commonly constructed.

In the construction of underframes of this type, especially where the center sill is made of an I-beam, either rolled or built up of 20 commercial sections, and the draft-sills are made of cast metal, the weakest place in these elements is at the point where one or the other is intersected by the body-bolster. In order to accommodate said body-bolster, 25 the vertical web, and sometimes the lower flange of the center sill and the draft sills are cut-away to permit them to arch over the same. This displacement of the metal of the center sill or the draft sill of necessary 30 weakens that particular portion of the underframe, and it is an object of my invention to construct the center-sill, bolster and draft sills in a novel manner, so that they may all be secured together in such a 35 manner, that none of the said members are weakened in any respect.

In a railway car underframe the draft and buffing gears are generally carried by the draft sills, which are connected to the center 40 sills of the car, and these connections are ordinarily relied upon to resist a large proportion, if not all, of the severe draft strains and buffing shocks to which the car is subjected when in use. As a consequence the 45 draft-beams, or their connections with the underframe, are frequently broken or overstrained.

Another object of my invention is to provide an underframe construction in which 50 the draft sills are connected to the body

bolsters in such a manner that the bolsters 55 rigidly brace the draft beams, and constitute strong abutments to receive and transmit the draft and buffing strains and shocks.

A further object of my invention is to provide an underframe structure in which 60 the draft sills are rigidly and securely attached to the body bolster in such a manner that they can readily be removed and replaced, without disturbing the bolster or removing any part of the latter.

Another object of my invention is a reduction in the number of the parts constituting my underframe, which I attain by making the draft sills in one piece, and the center bearing integral therewith.

With these and other objects in view, the present invention consists in the combination and arrangement of parts, as will be hereinafter more fully described, shown on the accompanying drawings, and particularly pointed out in the appended claims, it being understood that changes in the form, proportion, size and minor details may be made, within the scope of the claims, without departing from the spirit or sacrificing 80 any of the advantages of the invention.

In the accompanying drawings, in which like characters of reference designate corresponding parts in the various figures of the drawings, Figure 1 is a plan view of so much 85 of a car underframe as is necessary to illustrate my invention. Fig. 2 is a longitudinal section on the longitudinal center line of the car underframe, on line 2—2, Fig. 1. Fig. 3 is an enlarged horizontal sectional 90 view on line 3—3 of Fig. 2, showing a method of connecting together the center sill, body bolster and draft sills. Fig. 4 is a vertical section on line 4—4 of Figs. 1 and 3; Fig. 5 is a vertical section on line 5—5 of 95 Figs. 1 and 3; and Fig. 6 is a vertical section on line 6—6 of Figs. 1 and 3. Fig. 7 shows a modification of my invention, one half being a plan view of a portion of the underframe, and the other half a horizontal 100 sectional view on line 7—7 of Fig. 8. Fig. 8 is a longitudinal vertical section on line 8—8 of Fig. 7; Fig. 9 is a vertical section on line 9—9 of Fig. 7; Fig. 10 is a vertical

section on line 10—10 of Fig. 7 and Fig. 11 is a vertical section on line 11—11 of Fig. 7.

Referring now in detail to the drawings, 1, indicates the center sill which may be of 5 rolled I beam section or as is shown in the several figures of the drawings, may be built up of commercial bars and plates.

2 indicates the web plate, 3, 3 the compression flanges, and 4, 4 the tension flanges of 10 the center sill.

5, 5 indicate the two members forming the body bolster of the underframe, each of which is provided with side bearing devices of any preferred form. The outer ends of 15 these bolster members are provided with flanges 6, 6 to which the side sills 7, 7 are secured. The inner ends of the webs of the bolster, *i. e.*, those nearest to the longitudinal center line of the car, have their web 20 portions offset at 8, and at the point 9, where they contact with the end of the draft sill, assume an angle of about forty-five degrees, whence they continue backward as at 10 toward the longitudinal center of the 25 car in the plane parallel to and in contact with the web of the center sill to which they are secured in any suitable manner. The webs of the bolster members 5, 5 are further provided with flanges 11, 11 at their 30 lower edges to which the tension angles 4, 4 of the center sill are secured and with similar flanges 12, 12 at their upper edges to which the angles 3, 3 are secured, the tieplate 33 being in turn secured to the angles 3, 3.

35 The draft sills at each end of the underframe are composed of two longitudinal members 13, 13 of channel or other suitable section for the reception of the draft gear (not shown). At the end nearest to the 40 bolster, their web members are united by a flange 14, and the upper portion 15 of the center bearing member 22, which is chambered for the reception of the king-pin and to make the member as light as possible consistent with strength. The outer end faces 45 16, 16 of this member, nearest to the bolster are formed at an angle of about forty-five degrees to correspond with the angle formed by the portions 9 of the bolster with which 50 they contact, provision being made for bolts

55 which are passed through both members to secure them together. The end of the web of the draft sill is split and is of a V form at 18, to give strength and stiffness to this member at this point. The ends of the draft sill member also extend in the direction of the sides of the underframe in the form of webs 19, having flanges 20 on their upper sides to which a portion of the upper flange 35 of 60 the bolster, and the tieplate 33, are secured. Flanges 21 are also provided on the lower sides of the webs 19, which are secured to the lower flanges 34, 34 of the bolster members. In Fig. 2 of the drawings, the center

bearing 22, is shown in longitudinal vertical 65 section. The center bearing is made integral with the end of the draft sills nearest to the bolster, and consists of a substantially pan shaped member 23 united to the end of the draft sill member by the hollow portion 70 24, and braced thereto by brackets 25, provision being made for the king pin in the shape of the openings 26. An aperture 27, is made in the end portion of the draft sill member, so that the king pin can be withdrawn through this opening when desirable and thus obviating the necessity of removing the tie-plate 33, to withdraw the king pin through the top of the member.

Figs. 7 to 10 inclusive of the drawings 80 illustrate a modification of my invention, in which the bolts 17 shown in the other form of my invention are dispensed with, and in which rivets 28 may be used to secure together the portions 16 of the end of the draft 85 sill member and portions 9 of the bolster member, the construction being in other respects substantially the same as that shown in Figs. 1 to 6 inclusive. The car underframe is provided with the usual end sills 29 and gusset plates 30 and 31, to which diagonal braces 32 are secured in each corner of the underframe to counteract deformation of the underframe due to "poling" or shocks or strains applied to the corner of the underframe or superstructure which may be applied thereto.

Having thus described my invention, what I claim as new and desire to secure by Letters Patent is:—

1. An underframe for cars comprising a center sill, and a bolster having portions that lap past the end of said center sill and are secured thereto, a draft sill having ends that lap and are secured to said bolster, and a center bearing member integral with said draft sill.

2. An underframe for cars comprising a single center sill, and a bolster having end portions that lap past the end of said center sill and are secured thereto, a draft sill having ends that lap and are secured to said bolster, and a center bearing member integral with said draft sill.

3. An underframe for cars comprising a center sill and bolsters having end portions that lap past the end of said center sill and are secured thereto, draft sill members having ends at substantially right angles to their longitudinal portions, and which lap and are secured to said bolsters, the said longitudinal draft sill members being connected together by members forming the upper portions of the center bearing members, and center bearing members integral with said draft sill members.

4. An underframe for cars comprising a single center sill and bolsters having end

- portions that lap past the ends of said center sill and are secured thereto, draft sill members having ends at substantially right angles to their longitudinal portions, and 5 which lap and are secured to said bolsters, the said longitudinal draft sill members being connected together by members forming the upper portions of the center bearing members, and center bearing members integral with said draft sill members.
- 10 5. An underframe for cars comprising a center sill, bolsters having end portions that lap past the ends of the center sill and are secured thereto, between the upper and lower 15 edges thereof, and draft sills having ends that lap and are secured to the bolster members between the upper and lower edges thereof, and center bearing members formed integral with said draft sills.
- 20 6. An underframe for cars comprising a center sill, a two piece bolster member having end portions which meet and lap past the end of said center sill and are secured thereto, a draft sill member having ends 25 which meet and lap on said bolster, and are secured thereto, and a center bearing member integral with said draft sill member.
7. An underframe for cars, comprising a center sill, a bolster member made in halves, 30 the inner ends of each half meeting andlapping past the end of said center sill and secured thereto, a draft sill member having ends fitting into a V-shaped recess formed in said bolster member, and ends extending 35 laterally andlapping said bolster member and secured thereto, and a center bearing member integral with said draft sill member.
8. An underframe for cars, comprising a center sill, a bolster member made in halves, 40 the inner ends of each half meeting andlapping past said center sill member and secured to the web and top and bottom flanges thereof, a draft sill member having an end 45 fitting into a V-shaped recess formed in said bolster member, and ends extending laterally andlapping said bolster member and secured to the web and bottom flanges thereof, a tie plate secured to the top flanges of 50 the draft sill member, the bolster member and center sill, and a center bearing member integral with said draft sill member.
9. In an underframe for cars, a center sill, 55 a bolster comprising a plurality of parts, each of said parts having flanges which are secured to said center sill, draft sill members having a V-shaped end portion adapted to fit in said bolster, a center bearing member integral with said draft sill members, and bolt and rivet means for connecting said draft sill members and bolster.
- 60 10. In an underframe for cars, a center sill, a bolster comprising a plurality of members secured to said center sill, a draft sill
- having a converging end portion, said end 65 portion being adapted to fit in said bolster, and means for securing said bolster and draft sill together.
11. In an underframe for cars, a center sill, a bolster comprising a plurality of parts 70 secured to said center sill, a draft sill member having a V-shaped end portion, and means for securing said end portion and bolster together.
12. In an underframe for cars, a center 75 sill, a bolster comprising a plurality of parts secured to said center sill, draft sills having a V-shaped portion adapted to fit in said bolster, a center bearing member integral with said draft sills and bolt means for securing said draft sills and bolster together.
13. An underframe for cars comprising a center sill, a bolster having portions that lap past the end of said center sill, said portions being secured to the web of said sill, a draft 85 sill member having a V-shaped end portion adapted to fit in said bolster and means for securing said draft sill member and bolster together.
14. In a car underframe, a draft sill member having a V-shaped end portion, a center sill, bolster members secured to said center sill, said bolster members being shaped and arranged to receive the V-shaped end portion of said draft sill member and means for 90 securing all of said members together.
15. In a car underframe, a bolster comprising a plurality of parts, having their inner end portions extended in a direction toward the transverse center line of the underframe, a center sill terminating short of the longitudinal center line of the bolster and secured between the end portions of said parts, a draft sill member extending inwardly beyond the longitudinal center line 100 of said bolster and means for securing said bolster and draft sills together.
16. In an underframe for cars, a bolster comprising a plurality of members, a center sill terminating short of the longitudinal 105 center line of said bolster and secured between said members, a draft sill member extending inwardly beyond said center line, and means for securing said bolster and draft sill members together.
17. In an underframe for cars, a bolster comprising a plurality of members, a single center sill terminating short of the longitudinal center line of said bolster and connected with said members, a draft sill member having laterally projecting flanges secured to the webs of said bolster members, and a V-shaped end portion extending inwardly beyond the longitudinal center line 115 of the bolster and secured between said members and a cover plate connecting said center sill, bolster and draft sill member.
18. In an underframe for cars, a center

sill of substantially I-shape in cross section, a bolster comprising a plurality of integral I-shaped members having channel shaped inner end portions secured within the end 5 of said center sill, a draft sill member having an integral V-shaped end portion adapted to fit in said bolster and be secured to said members, and a cover plate connecting

said center sill bolster members and draft sill member.

10

In testimony whereof I affix my signature in presence of two witnesses.

BURNS D. LOCKWOOD.
